UNITED STATES PATENT OFFICE.

CARL O. LINN, OF SALINA, KANSAS.

EXTENSION RULE.

Application filed June 9, 1925. Serial No. 35,934.

The invention relates to extension rules, and has for its object to provide a device of this character comprising a plurality of telescoped metallic sections having overlying registering flanges in slidable engagement with each other and means carried by the ends of the sections and cooperating with each other for limiting the inward and outward movement of the sections in relation to each other, thereby maintaining the sections in registration when in contracted position, and preventing the sections from coming out of interengagement with each other when extended.

A further object is to provide one of the ends of the sections with semicircular recesses and lugs, which recesses when the rule is contracted receives the lugs and limits the inward movement thereof.

A further object is to provide the flanges of the sections at one of their ends with outwardly extending lugs forming shoulders, and lugs carried by the other ends of the sections extending downwardly and overlying the edges of the flanges in the path of the outwardly extending lugs for limiting the movement of the sections when the rule is extended.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawing:

Figure 1 is a perspective view of the rule in closed position, and within a casing.

Figure 2 is a top plan view of the rule casing.

Figure 3 is a perspective view of the rule showing the same partially extended.

Figure 4 is a vertical longitudinal sectional view through the ends of two of the rule sections showing the limiting means.

Referring to the drawing, the numeral 1 designates a plurality of telescoped rule sections, which sections are provided with graduations 2 for measuring purposes. The sections 1 are provided with slidably engaged inwardly extending flanges 3 and 4, which flanges when the rule is in collapsed position register with each other, and which are slidably engaged when the

flanges 4 at one of their ends are provided with inwardly extending lugs 5 formed integral therewith, which lugs, when the rule sections are extended, engage the downwardly extending integral lugs 6, which overlie the inner edges of the flanges 4 and limit the outward movement of the rule sections in relation to each other when the rule is extended for use. 60 Flanges 4 adjacent one of their ends are provided with upwardly extending lugs 7, which lugs are out of alignment with each other and are received in recesses 8 in the adjacent ends of the flanges 4 for limiting 70 the inward movement of the rule sections and substantially holding the same when in collapsed position in registration as clearly shown in Figures 1 and 4. The rule sections are made from sheet metal stamped to form, 75 therefore accuracy is assured at all times as well as a durable rule. It will also be seen as many rule sections as desired may be used, and a relatively long rule may be provided, which will collapse into a small 80 package, thereby allowing the same to occupy a minimum amount of room in the pocket of the user, and by forming the device from metal it is obvious the rule will not be easily damaged or the graduations 85 obliterated incident to constant use of the rule, which is a common difficulty now experienced with wooden rules.

From the above it will be seen a telescoping rule is provided which is extremely simple in construction, formed from sheet metal, stamped and bent to form, and the limiting means for limiting the movement inwardly and outwardly of the telescopically engaged sections is simple in construction 95 and will not interfere with the use of the rule during a measuring operation.

The device is preferably provided with a tubular casing 9 in which the rule may be stored when not in use, thereby protecting 100 the same from accumulation of dirt between the slidably engaged parts.

The invention having been set forth what is claimed as new and useful is:

1. A rule comprising a plurality of sections, each longitudinally chambered from end to end, the sections being slidably telescoped one within the other, the wall of each section except the innermost, being recessed at one end, the recessed ends being adjacent when the sections are closed together and the recesses of adjacent sections 110

- being laterally off-set with relation to one another and all the sections, except the innermost, being provided adjacent their recessed ends with outwardly projecting lugs, each adapted, when the sections are closed together, to enter the recess of the outwardly adjacent section and to abut against the end wall of the recess to thus limit the inward movement of the sections.
- 10 2. A rule comprising a plurality of longitudinally chambered sections, slidably telescoped one within the other, the chambers of each section, except the outermost, being formed in part by oppositely and inwardly bent longitudinal flanges, the corresponding flanges of the different sections being in superposed relation, thus forming two sets

of superposed flanges, one of the corresponding ends of one set being each recessed, there being adjacent the other ends of said set lugs 20 projecting from the lateral edges of the flanges, the recess of each flange being laterally off-set with relation to those of adjacent flanges and the recessed ends being also provided with outwardly projecting lugs, 25 each positioned to enter the recess of the adjacent superposed flange, when the sections are closed together, and with inwardly bent lugs, each adapted to abut against the lateral-edge lug of the inwardly adjacent 30 flange when the rule is distended.

In testimony whereof I have signed my name to this specification.

CARL O. LINN.
